UNITED STATES PATENT OFFICE

THEODORE M. PAGE, OF LOS ANGELES, CALIFORNIA

PIPE GRIP

Application filed March 20, 1929. Serial No. 348,461.

This invention relates to improvements in pipe grips and the like.

An object of the invention is to provide an improved pipe grip which is of novel, simple and durable construction and which has been primarily designed to be used upon an apparatus for well drilling although it may be used under analogous circumstances, such as upon pipe rams.

Another object of the invention is to provide a pipe grip having a body through which pipe is adapted to be extended and which has a plurality of movable jaws or slips pivotally mounted thereon adapted to be actuated in unison and moved into or out of engagement with the pipe to resist its moving through the body. By having the jaws pivotally mounted upon the body the improved pipe grip can be very advantageously employed upon a well drilling apparatus and has the advantage that there is no danger of the slip being dropped into the well hole requiring a fishing operation.

Another object of the invention is to provide a pipe grip having movable jaws or slips which is adjustable in that the pipe grip may accommodate pipes of various sizes and regardless of the size of the pipe the jaws will properly engage it and snugly fit around it.

With the foregoing and other objects in view which will be made manifest in the following detailed description and specifically pointed out in the appended claims, reference is had to the accompanying drawings for an illustrative embodiment of the invention, wherein:

Fig. 1 is a partial view in elevation, parts being broken away and shown in vertical section illustrating the invention as being used upon a well drilling apparatus and accommodating a pipe of one size.

Fig. 2 is a view similar to Fig. 1 illustrating the pipe grip as engaging and supporting a pipe of a different size.

Fig. 3 is a top plan view of the improved pipe grip, parts being broken away and shown in horizontal section.

Fig. 4 is a vertical section taken substantially upon the line 4-4 upon Fig. 3.

Referring to the accompanying drawings

wherein similar reference characters designate similar parts throughout, the improved pipe grip comprises a cylindrical open topped body 10 which when the device is designed for use on a well drilling apparatus is of such size that it will fit properly in the rotary table T. In the bottom of the body 10 there is formed a central aperture 11 through which the pipe P is adapted to be extended. At intervals around the interior of the body there are formed sets or pairs of inwardly extending ears 12, each pair of ears providing supports within the body for a jaw or slip. Pintles 13 arranged in the same plane, extend through the ears and are rotatably mounted thereon and each pintle serves to pivotally support a jaw or slip 14 which is keyed or pinned as by pins 15 to its respective pintle. As clearly shown upon Fig. 3 the ends of the pintles have balls 16 formed thereon and at the bases of the balls there are formed gear teeth 17 forming a crown gear about the ball where it joins the body of the pintle. Connecting members 18 have semi-spherical recesses 19 formed in their ends so as to partially receive the balls and about these recesses they have formed on their ends gear teeth 20 which mesh with the gear teeth 17. In this manner the connecting members 18 serve to gearedly connect all of the jaws 14 together so that on rotation of one of the pintles 13 or a connecting member 18 all of the jaws will be caused to move inwardly or outwardly in unison. One of the connecting members 18 is provided with an upwardly extending handle 21 which is adapted to be oscillated back and forth to move the jaws or slips 14 inwardly or outwardly.

As clearly shown upon the drawing the engaging surfaces on the jaws or slips 14 are eccentrically arranged with respect to their axes of rotation so that the jaws may be caused to engage a pipe of large diameter or a pipe of small diameter merely causing the slips to swing inwardly toward each other. As clearly shown upon the drawing the side faces of the slips converge upwardly to enable them to fit together about a pipe of small diameter. On the engaging surfaces

of the slips there are formed teeth 22. The radii of curvature of the various teeth vary from the bottoms of the engaging surface to their tops. In other words, the teeth near the bottoms of the slips have a greater radius of curvatures than the teeth adjacent the tops of the slips and the radius of curvature of the various teeth gradually decreases from the bottom of the slips to the top. As clearly shown in Fig. 2, if the improved pipe grip is gripping upon a pipe of large diameter the lower portions of the slips will be those portions which are in engagement with it. The radius of curvature of the teeth on these portions of the slips is exactly equal to the radius or half the diameter of the pipe. In a similar manner when the smaller sized pipe is being engaged as shown in Fig. 1 upper portions of the slips are in engagement with the pipe and the radius of curvature of the teeth at these portions is exactly equal to half the diameter of the pipe. In this manner, regardless of the size of pipe which may be used on moving the slips inwardly toward each other they will engage the pipe at some point on their engaging surfaces and whatever point this may be a tooth or teeth will be located at it which has a radius of curvature such that it will fit snugly about the pipe.

From the above described construction it will be appreciated that an improved pipe grip has been provided which is self-adjusting to accommodate various sizes of pipe. The improved pipe grip can be advantageously employed to support drill pipe and the like in a well drilling apparatus and has the advantage that a single operator can cause all of the slips to be simultaneously actuated and moved into engagement with the pipe to support it or be disengaged therefrom. Also, there is no danger of the slips being dropped into the hole as in the case where slideable slips are employed which are separately removed by hand. The improved pipe grip has all of the advantages of prior grips in that the greater the load on the pipe the tighter the slips will be caused to engage it so that there is no danger of the pipe slipping between the slips.

While the drawing illustrates the slips as being operable by the manually actuated handle 21 it is to be understood that any other suitable form of actuating means may be substituted therefor if found desirable.

Various changes may be made in the details of construction without departing from the spirit or scope of the invention as defined by the appended claims.

I claim:

1. A pipe grip comprising a body through which pipe may be passed, a plurality of slips, pintles on which the slips are mounted rotatably upon said body, said pintles having balls formed on their ends, connecting members fitting between the balls, there being a

geared connection between the connecting members and the pintles, and means for rotating one of the connecting members to cause the slips to be actuated in unison.

2. A pipe grip comprising a supporting structure, a plurality of slips pivotally mounted upon the supporting structure for rotation about non-parallel axes in the same horizontal plane, said slips presenting eccentric toothed surfaces, and rotatable means connecting the slips for causing them to rotate in unison. 70

3. A pipe grip comprising a supporting structure, a plurality of slips pivotally mounted upon the supporting structure for rotation about non-parallel axes in the same horizontal plane, said slips presenting eccentric toothed surfaces, rotatable means connecting the slips for causing them to rotate in unison, and means for rotating said rotatable means. 80

4. A pipe grip comprising a supporting structure, a plurality of slips pivotally mounted upon the supporting structure for rotation about non-parallel axes in the same horizontal plane, said slips presenting eccentric toothed surfaces, and rotatable means rotatable about axes in said plane connecting the slips for causing them to rotate in unison. 90

5. A pipe grip comprising a supporting structure, a plurality of slips pivotally mounted upon the supporting structure for rotation about axes in the same horizontal plane, said slips presenting eccentric toothed surfaces, connecting means arranged between the slips, seats at the ends of the connecting means enabling the connecting means to rotate with the slips, there being toothed connections between the slips and the connecting means whereby the slips may be rotated in unison by the connecting means, and means for rotating the connecting means. 100

In testimony whereof I have signed my name to this specification.

THEODORE M. PAGE.
